Attorney

UNITED STATES PATENT OFFICE.

HERBERT H. WATKINS, OF HOMER, LOUISIANA.

RECTILINEAR PUMP.

Application filed May 29, 1924. Serial No. 716,809.

To all whom it may concern:

Be it known that I, HERBERT H. WATKINS, a citizen of the United States of America, residing at Homer, in the parish of Clairborne and State of Louisiana, have invented certain new and useful Improvements in Rectilinear Pumps; and I do hereby declare that the following is a full, clear, concise, and exact description of the invention, such 10 as will enable others skilled in the art to which it appertains to make and use the same.

This invention relates to improvements in rectilinear pumps, having for an object to 15 provide an oil pump adapted to elevate oil from a well into a settling or sand trapping compartment, whereupon such oil is removed from that compartment into a relaying compartment, whereat it is subjected to 20 pressure sufficient to cause discharge of the same therefrom and its flow from suitable conducting means.

Another and equally important object of 25 the invention is to provide a pump of the opposed or tandem piston type, wherein one of said pistons serves to lift the oil and draw the same into the settling compartment as well as from the same, while the other piston serves to force the oil lifted by the first 30 piston from the pump cylinder into a relaying compartment, to impart pressure thereto sufficient to effect its discharge from the pump.

Other objects of the invention will be in 35 part obvious, and in part pointed out hereinafter.

In order that the invention and its mode 40 of operation may be readily understood by persons skilled in the art, I have in the accompanying illustrative drawings, and in the detailed following description based thereupon, set out one possible embodiment of the same.

In these drawings: 45 Figure 1 is a side elevation of the improved pump showing the same arranged in a well bore and connected with suitable operating mechanism; and,

Figure 2 is an enlarged longitudinal section through the improved pump.

Having more particular reference to the drawings, in connection with which like characters of reference will designate corresponding parts throughout, the improved 50 pump may be stated to comprise a cylindri-

cal barrel 1 having its upper and lower ends engaged with reducer connections 2 and 3 respectively, the reduced open ends of the reducer 2 serving as the inlet port for the pump, whereas the open outer end of the reducer 3 serves as an outlet port for the pump. The barrel 1, as will be noted, is composed of several sections having the adjacent ends thereof internally screw threaded and interconnected by means of a combined coupling and partition, generally indicated by the numeral 4, said coupling having circular screw threaded portions adapted to be engaged with the correspondingly threaded adjacent ends of the barrel sections, as is clearly shown in the Figure 2, thereby dividing said barrel into superposed compartments 5 and 6, the compartment 5 serving as a settling compartment or sand trap, while the compartment 6 serves as a 60 relaying compartment from which the oil is forced by way of the outlet of the pump into suitable conduits for discharge therefrom.

A sand pipe 7 having a screw threaded lower end is turned into engagement with an internally screw threaded portion 8 of the reducer 2 and has a spherical valve cage 9 secured to the upper end thereof, as clearly shown in the Figure 2, while a spherical valve 10 is arranged within said cage and is adapted to normally seat upon the open upper end of the sand pipe 7, thus providing a suitable sand valve, common in pumps of this character.

Pump cylinder sections 11 and 12 are arranged within the barrel 1 and disposed longitudinally thereof, as clearly shown, the adjacent ends of said sections being externally screw threaded and turned into engagement with correspondingly threaded portions of the combined coupling and partition 4, thus immovably securing the same with respect to the several compartments 5 and 6 of the barrel 1. The lower portion of the section 12, as will be noted, is formed with a plurality of circumferentially disposed ports 13, the purpose of which will be hereinafter described, while the upper end of such section 12 terminates at a point directly below the outlet end of the reducer 3 engaging the upper end of the pump barrel 1.

Arranged for rectilinear movement in the section 11 of the pump cylinder, which as will be noted is arranged within the lower 100

compartment 5, is a valved piston generally indicated herein by the numeral 14, such piston as is usual in devices of this character being provided with a suitable form of 5 spherical valve or similar device 15. Another piston 16 is arranged within the section 12 of the pump cylinder for rectilinear movement, but as will be noted, this particular piston is of solid formation and has the 10 packing cups 17 thereof inverted with respect to the packing cups of the valved piston 14. A connecting rod 18 is arranged between the several pistons 14 and 16 and is connected thereto in the manner clearly indicated 15 in the Figure 2, thus causing said pistons to be moved collectively. Also, the upper end of the solid piston 16 is connected to the lower end of the usual sucker rod 19 extending 20 upwardly through the outlet port of the reducer 3 and through a suitable oil discharge conduit 20 to the mouth of the well, whereupon it is passed through a suitable packing or stuffing gland 21 and is pivotally connected, as indicated at 22, to suitable operating mechanism, generally indicated herein 25 by the numeral 23.

The modus operandi of my improved pump may be stated to be as follows:—

30 With up stroke of the pistons 14 and 16, oil will be drawn by way of the inlet port of the reducer 2 through the stand valve 10 into the lower or settling compartment 5 of the pump barrel 1. Sand or similar 35 matter contained in the oil, of course, will be trapped in said compartment 5, settling to the bottom thereof by gravity. During this up stroke of the piston 14, it will of course be understood that the suction created thereby will be sufficient to remove the 40 spherical valve 10 from the open upper end of the sand pipe 7, permitting such ingress of oil to the compartment 5. As the piston 14 is returned in the cylinder section 11 upon its down stroke, that oil which is within the compartment 5 of the barrel 1 will be caused to move through said valved piston 14, unseating the spherical valve 15 and passing into the upper portion of such cylinder section 11 and thereupon into the cylinder section 12 beyond the spherical valve 15 of the piston 14. With movement of the oil into the upper portion of the cylinder section 11 and into the cylinder section 12, 50 it will be understood that a portion of the same will drain or pass through the ports 13 into the relaying compartment 6. Also, it will be understood that by reason of the downwardly moving solid piston 16 which 55 is collectively movable with the piston 14, pressure will be imparted to such body of oil sufficient to cause forcing of the same from the relaying compartment 6 through the outlet opening or port of the reducer 3 and to the conduit 20 from whence it will 60

be discharged. This operation of the pump, of course, will be recurring, and in consequence, the production of a steady stream of oil from the outlet end of the conduit 20 will be produced.

70 From the foregoing, it will be seen that I have provided a simple, yet highly practical form of oil pump of the tandem piston type, wherein the pump in addition to serving as an elevating means for oil, will 75 serve as an effectual sand trap, thus preventing the passage of the sand into the pump cylinders with the resultant cutting and deterioration of the cups of the pistons 14 and 16 as well as the valve of the piston 14.

80 Also, it will be appreciated that by reason of the fact that the oil is not forced from the tubing or conduit 20 upon the upward stroke of the pistons 14 and 16, a material strain upon the pump operating mechanism 85 will be removed, and hence, the period of usage thereof will be materially increased.

Furthermore, because of the fact that the oil is forced out of the conduit or tubing 20 upon the downward stroke of the pistons 14 and 16, it will be understood that 90 lightening of the load or stress upon the pump operating mechanism will occur and furthermore, the inert weight of the pistons as well as the connecting rod 13 and 95 the sucker rod 19 will be utilized in the pressure exerting and oil discharging function carried out upon downward stroke of said pistons 14 and 16.

Likewise, because of the fact that the valved piston 14 working within the lower section 11 of the pump cylinder is arranged at a greater distance 100 from the sand valve 10 than in those forms of oil pumps now prevalent, it will be understood that an added space or area for oil within the compartment 5 will be provided and that this quantity of oil will serve to cushion the "pound" of the oil well which usually occurs upon the downward stroke of the pistons and rods.

110 Manifestly, the construction shown is capable of considerable modification, and such modification as is within the scope of my claims, I consider within the spirit of my invention.

115 I claim:—

1. A pump of the character described comprising a barrel having inlet and outlet ports in its opposite ends, and divided into superposed compartments, a sand valve arranged in the barrel in proximity to its inlet port, a cylinder disposed longitudinally of the barrel and fixedly supported therein, a valved piston working in that portion of said cylinder within the lower barrel compartment, a solid piston working in that portion of said cylinder within the upper barrel compartment, a portion of the cylinder within the upper compartment having ports in the same, and means for col- 120 125 130 135 140

lectively connecting said pistons and permitting the transmission of rectilinear motion thereto.

2. A pump of the character described comprising a barrel composed of longitudinally aligned sections, a combined coupling and partition wall connecting the adjacent ends of said sections and dividing the same into superposed compartments, reducers engaged in the opposite ends of said barrel forming inlet and outlet ports for the same, a sand valve arranged in proximity to the inlet port and within the lower valve compartment, a cylinder disposed longitudinally of the barrel composed of sections having their adjacent ends connected to adjacent portions of said combined coupling and partition, a valved piston working within said section of said cylinder with 15 in the lower barrel compartment, a solid piston working in that portion of said cylinder section within the upper barrel compartment, a portion of the cylinder section within the upper barrel compartment having circumferentially disposed ports therein, and 20 means for interconnecting said pistons and facilitating transmission of rectilinear motion thereto.

3. A pump of the character described comprising a barrel composed of cylindrical longitudinally aligned sections, a combined coupling and partition element arranged between the adjacent ends of said barrel sec-

tions and connected to the same, reducers engaged in the opposite ends of said barrel 35 formed with ports whereby to permit of ingress and egress of oil to and from said barrel, said combined coupling and partition dividing the pump barrel into superposed compartments, a sand pipe supported 40 upon the reducer engaged with the lower end of said pump barrel and extending upwardly for a distance into the lower compartment of said barrel, valve means operatively associated with the upper end of said 45 sand pipe, a pump cylinder comprising sections having their adjacent ends engaged with adjacent portions of said combined coupling and partition immovably arranged and disposed longitudinally of said pump 50 barrel, a valved piston working in that portion of said cylinder section within the lower barrel compartment, a solid piston working in that portion of said cylinder section within the upper barrel compartment, 55 a portion of the cylinder section within the upper barrel compartment having circumferentially disposed ports formed therein, means for interconnecting said pistons, and other means connected to the pistons for 60 facilitating the imparting of a rectilinear motion thereto.

In witness whereof I have hereunto set my hand.

HERBERT H. WATKINS.
